Des. 110,689

UNITED STATES PATENT OFFICE

110,689

DESIGN FOR AN ASHTRAY

James D. Cannon, Nashville, Tenn.

Application May 21, 1938, Serial No. 77,340

Term of patent 7 years

To all whom it may concern:

Be it known that I, James D. Cannon, a citizen of the United States, residing in Nashville, county of Davidson, and State of Tennessee, have invented a new, original, and ornamental Design for an Ashtray, of which the following is a specification, reference being had to the accompanying drawing, forming part thereof.

Figures 1 and 2 are perspective views from opposite sides of an ashtray embodying the present design.

I claim:—

The ornamental design for an ashtray, as shown.

JAMES D. CANNON.
